218,427

COMBINED HAND DRYER AND ADVERTISING DISPLAY

Louis E. Beyer, Bellwood, Ill. (% Electric Aire Engineering Corp., 7908 W. Grand Ave., Elmwood Park, Ill. 60635)

Filed June 20, 1969, Ser. No. 17,788

Term of patent 14 years

Int. Cl. D23—02; D20—03

U.S. Cl. D23—74

Fig. 2

Fig. 1

FIG. 1 is a front elevational view of a combined hand dryer and advertising display embodying the new design; FIG. 2 is a top plan view thereof;

FIG. 3 is an end view thereof looking from the right in FIG. 1; and

FIG. 4 is a bottom view thereof.

The end not shown is a mirror image of FIG. 3.

I claim:

The ornamental design for a combined hand dryer and advertising display, as shown and described.
